UNITED STATES PATENT OFFICE.

ARTHUR R. MOSLER, OF NEW YORK, N. Y.

BOX.

Application filed December 7, 1926. Serial No. 153,071.

The object of my invention is to provide a box for holding a supply of clamp parts in convenient position for use. My improved box includes, among other features, 5 a compartment containing a clamp band supply roll and a compartment containing a supply of clamp buckles, band winding keys and their operating bars.

My box also may be provided with markings whereby the desired band lengths for use in connection with articles of various sizes may be withdrawn and severed from the roll, leaving a sufficient amount of exposed end portion to be folded over a portion 15 of the buckle to be used therewith.

A practical embodiment of my invention is represented in the accompanying drawings, in which:

Fig. 1 represents my box in top plan, portions of the cover and partition being broken away to expose the parts beneath the same.

Fig. 2 represents the box in side elevation.

Fig. 3 represents the box in vertical central section taken in the plane of the line 25 III—III of Fig. 1, looking in the direction of the arrows.

The box is shown as comprising a cylindrical body portion and a removable cover, the body portion being divided by a horizontal 30 removable partition into a lower compartment for the clamp band supply roll 1 and an upper compartment for the other clamp parts comprising the clamp buckles 2, the winding keys 3 and their operating bars 4.

The body portion of the box has a substantially flat bottom 5 and uprising sides 6, while the cover is shown as having a substantially flat top 7 and depending sides 40 8 which overlap the uprising sides 6 of the body portion.

A vertically elongated slot 9 is formed in the uprising sides 6 of the bottom, through which slot the free end of the roll band is drawn for subsequent severance into lengths to be used with the buckles to form the clamp for hose or other articles. The walls of the slot are shaped to permit the withdrawal of the clamp band along a line substantially tangential to the roll for preventing 45 unintentional distortion of the band.

The box may bear markings denoted as a whole by 10, indicating how great a band length is required for wrapping and clamping a cylindrical article of a certain diameter, which markings in the present instance

are shown on the exterior of the cover top 7.

The container also has calibrations 11 (in the present instance in inches) around the exterior of its sides for use in measuring off 60 lengths of band required, said calibrations beginning at a certain distance spaced from the slot 9 to indicate where the band is to be severed for leaving the required amount of exposed end to be folded over the next 65 succeeding buckle.

The uprising sides 6 of the body portion are distorted outwardly to form an exterior circumferential rib 12 and corresponding inner circumferential groove 13, the rib 12 70 in the present instance serving as a stop for the depending sides 8 of the cover.

The partition which divides the box into upper and lower compartments is shown as a removable tray 14. To prevent the unintentional removal of the clamp roll 1 when the tray is removed, I provide a retaining member in the form of a flat spring bar 15, the opposite ends of which are snapped into the circumferential groove 13 at diametrically opposite points. A new band supply roll may be inserted by removing 80 the cover, the tray and the retaining member 15.

The procedure for making a clamp is as follows: The doubled-over free exposed end of the roll band with its buckle is drawn outwardly through the slot 9 along a line substantially tangential to the roll and wrapped around the sides of the box to measure the length required for use in clamping an article of a predetermined circumference. When a sufficient length of band has been withdrawn, the band is severed at the zero 90 mark of the calibrations, thus leaving a sufficient amount of the free end of the band exposed for permitting it to be folded over the next buckle to be used, said buckle being taken from the supply in the upper compartment of the box.

It will thus be seen that I have provided a box which will keep the clamp supply parts together so that a clamp may be quickly made of the desired length, said box being arranged for the ready reception of new band supply rolls and other clamp supply parts as it becomes necessary.

What I claim is:—

1. A box for containing clamp supply parts including a clamp band roll, the sides 110 of the box having a slot through which the band may be withdrawn, and a removable

tray forming a partition for dividing the interior of the box into a compartment for the band roll and a compartment for the other supply parts.

- 2. A box for containing clamp supply parts including a clamp band roll, the sides of the box having a slot through which the band may be withdrawn, a removable tray forming a partition for dividing the interior 10 of the box into a compartment for the band roll and a compartment for the other supply parts, and a removable member engaging the box for retaining the band roll in position within the box against unintentional removal therefrom.
- 15 3. A box for containing clamp supply

parts, including a clamp band roll, the sides of the box having a slot through which the band may be withdrawn, a removable tray forming a partition for dividing the interior 20 of the box into a compartment for the band roll and a compartment for the other supply parts, the sides of the box having an inner circumferential groove, and a removable flat spring extending across the box and having 25 its ends snapped into said groove for retaining the band roll in position within the box against unintentional removal therefrom.

In testimony, that I claim the foregoing as my invention, I have signed my name this 30 2nd day of December, 1926.

ARTHUR R. MOSLER.
